UNITED STATES PATENT OFFICE.

HENRY REISCHMANN, OF NEW ROCHELLE, NEW YORK.

DESIGN FOR A FOOT-REST FOR STOOLS AND THE LIKE.

42,773.

Specification for Design.

Patented July 9, 1912.

Application filed March 30, 1912. Serial No. 687,505. Term of patent 14 years.

To all whom it may concern:

Be it known that I, HENRY REISCHMANN, a citizen of the United States, residing at New Rochelle, in the county of Westchester and State of New York, have invented a certain new, original, and ornamental Design for Foot-Rests for Stools and the Like, of which the following is a specification.

The accompanying drawing shows the design in Figure 1, in perspective, as seen from the front, the stool being shown in dotted outline; in Fig. 2 in plan.

The design consists in the arc-shaped foot-rest proper *a*, the embracing portion *b* adapted to be fitted to the pedestal *c* of the

stool or the like *d*, and the means *e* whereby the foot-rest proper *a* is connected to the embracing portion *b* in spaced relation thereto.

I claim:

The ornamental design for a foot-rest for stools and the like, substantially as herein shown and described.

In testimony whereof I affix my signature in presence of two witnesses.

HENRY REISCHMANN.
